UNITED STATES PATENT OFFICE.

NIAL W. KELDER, OF BRIDGEPORT, CONNECTICUT.

LIQUID-FUEL BURNER.

1,362,010.

Specification of Letters Patent. Patented Dec. 14, 1920.

Application filed December 12, 1919. Serial No. 344,440.

To all whom it may concern:

Be it known that I, NIAL W. KELDER, a citizen of the United States, residing at Bridgeport, in the county of Fairfield and 5 State of Connecticut, have invented certain new and useful Improvements in Liquid-Fuel Burners, of which the following is a specification.

My invention relates to new and useful 10 improvements in liquid fuel burners, and the primary object of the invention is to provide a device wherein air is evenly admitted and combined with the fuel flame to cause the flame to burn evenly and deliver the 15 greatest amount of heat and to combine the elements of combustion whereby an odorless and smokeless flame is established.

Another important object of the invention 20 is to provide a device of the above nature, the construction of which is generally improved and manufacturable at a minimum cost, which is strong, durable, easily installed in stoves and ranges, and is highly efficient in practice.

25 A further object of the invention is to provide a device including a flame chamber consisting of a pair of spaced perforated walls, the perforations therein being so arranged that the air admitted therethrough 30 is directed upwardly of the flame chamber upon being admitted thereinto.

A still further object of the invention is 35 to provide a device of the above nature including a burner which is constructed from a single piece of material in such a manner as to form supports for parts associated with the burner.

Other objects and advantages of the 40 invention will become apparent during the course of the following description.

In the accompanying drawings forming a part of the description and wherein like numerals are employed to designate like parts throughout the several views,

45 Figure 1 is a side elevation of the invention applied to a stove or range,

Fig. 2 is a fragmentary vertical section of my improved burner,

Fig. 3 is a bottom plan of the same,

50 Fig. 4 is an enlarged fragmentary vertical section of a portion of the flame chamber walls.

In the drawings, wherein for the purpose of illustration is shown a preferred embodiment of the invention, the numeral 5 designates a stove, range or any other heating de-

vice, in which my improved burner may be installed for cooking or heating purposes. A fuel reservoir 6 is provided to supply my improved burners designated in its entirety 60 by the numeral 7, with fuel and to maintain the fuel at a constant level within the burner. The fuel from the reservoir is passed to the burner through a supply conduit 8, including a vertical branch 9, the upper end of 65 which terminates in upwardly inclined radiating feed pipes 10, the upper ends of which communicate and deliver fuel to the fuel chamber of the burner.

The burner, is designated in its entirety 70 by the numeral 11 and consists of a single piece of material bent vertically upon itself intermediate its ends to provide a dividing partition 12, and the free ends 13 of the material are extended upwardly upon either 75 side of the partition in spaced relation thereto in order to provide an outer cylinder receiving socket 14 and an inner wick and fuel chamber or socket 15. The burner 11 is an annular device, and the fuel chamber 15 80 thereof receives in its upper end, an annular wick 16 which may consist of any desired material, but is preferably formed of asbestos in the present instance. As more clearly shown in Fig. 2 the upper ends of 85 the feed pipes 10 extend through the bottom of the fuel chamber 15 to deliver fuel to the bottom of the chamber and thence to the wick.

A perforated circular air admitting plate 90 17 is provided with an upstanding annular flange 18 by which the plate is secured to the inner wall of the wick and fuel chamber 15, through the medium of fastening elements 19.

An outer perforated cylinder 20 has its lower end snugly received in the cylinder receiving socket 14 of the burner to be properly supported, and to form the outer wall of a flame chamber 21. The inner wall 100 of this chamber is provided by a perforated cylindrical drum 22, the top 23 of which is provided with a single central aperture 24, while the bottom of the drum is open and snugly engaged by the upstanding annular 105 flange of the perforated air admitting plate 17. Consequently, the drum is arranged concentrically of the cylinder 20 in spaced relation thereto so as to provide the flame chamber 21.

The air admitting apertures 25 in both the drum and the cylinder as more clearly shown

in Figs. 2 and 4, are provided by equipping said elements with alined horizontal slits. The upper edge 26 of each slit in the cylinder is concaved outwardly while the lower edges 27 are concaved inwardly to equip the cylinder with upwardly inclined apertures. The upper edge of each slit in the drum 22 is concaved inwardly, while the lower edges 29 are concaved outwardly to form upwardly inclined apertures or openings in the drum, and consequently due to the arrangement of these openings and the partial vacuum created in the flame chamber, air will be drawn through the apertures in an upward direction upon opposite sides of the flame to properly combine with and intensify the same.

In use, fuel being constantly maintained in the fuel chamber 15 of the burner, the wick 16 is ignited and due to the partial vacuum created in the flame chamber 21, air is sucked up through the perforated plate 17 and through the apertures in the drum 22 and through the apertures in the outer cylinder 20. Consequently, air will be contacted with the flame upon both sides thereof and due to the incline relation of the apertures 25, the heat will be assisted in reaching its destination while the air is properly combining with the flame.

It will be appreciated that the burner may be easily and readily disassembled as the outer cylinder 20 may be moved out of its socket 14 as can the drum 22 be disengaged from the flange 18 of the air admitting plate 17. After the cylinder 20 has been removed, it will be manifest that the wick may be trimmed or replaced and the removed parts of the burner may be quickly assembled.

The foregoing description and accompanying drawings have reference to what might be considered to be the approved or preferred form of my invention. I desire

it to be understood that I may make such changes in the construction, combination and arrangement of parts, materials, dimensions, et cetera, as may prove expedient and fall within the scope of the appended claims.

Having thus fully described my invention what I claim as new and desire to secure by Letters Patent, is:—

1. A burner comprising a drum into which air may pass, a cylinder surrounding said drum in spaced relation to provide a flame chamber, and the walls of said drum and cylinder being provided with upwardly inclined openings directed inwardly toward the flame chamber.

2. A liquid fuel burner comprising a flame chamber, the walls of said chamber being equipped with a plurality of horizontal slits, the lower edges of which are bent inwardly of the chamber, and the upper edges are bent outwardly of the chamber to form a plurality of upwardly and inwardly inclined openings.

3. A device of the class described comprising a burner, a perforated cylinder, a perforated drum mounted concentrically and in spaced relation to said cylinder, a wick, said burner consisting of a single piece of material having its intermediate portion bent vertically upon itself to form a dividing partition, the ends of said material being bent upwardly in spaced relation to said dividing partition to form a pair of sockets, the innermost for the reception of said wick, and the other for the reception of the lower end of the cylinder.

In testimony whereof I affix my signature in presence of two witnesses.

NIAL W. KELDER.
